UNITED STATES PATENT OFFICE.

HARRIET E. KELLEY, OF DENVER, COLORADO.

COAT-HANGER.

1,379,105.

Specification of Letters Patent.

Patented May 24, 1921.

Application filed March 17, 1921. Serial No. 453,071.

To all whom it may concern:

Be it known that I, HARRIET E. KELLEY, a citizen of the United States, residing at Denver, in the county of Denver and State 5 of Colorado, have invented a new and useful Coat-Hanger, of which the following is a specification.

The device forming the subject matter of this application is adapted to be used for 10 suspending coats and like garments, and the invention aims to provide a hanger wherein relative movement between parts thereof is positively prevented, the construction of the device being such that, when a garment is 15 suspended thereon, the garment will not lose any shape which it may have assumed, due to peculiarities in the shape of the shoulders and the neck of the wearer.

In the drawings:—Figure 1 shows in elevation, a device constructed in accordance with the invention; Fig. 2 is a detail enlarged from Fig. 1; Fig. 3 is a section on the line 3—3 of Fig. 2.

The hanger claimed preferably is made of 25 somewhat stiff wire and embodies a base 1 having angularly disposed end members 2 merging into arms 3 which slant toward the base 1 to define prominent projections 4 at the points where the end members 2 join the 30 arms 3, the arms merging into top members 15 and 5, which slant away from the base 1. One top member 15 is bent upon itself to define an angle 6 and to define a first suspension member 7 and a second suspension member 35 8, located side by side, the members 7 and 8 being connected at their upper end by an eye, 9. The top member 5 is lodged, as shown at 10, in the angle 6 formed by the parts 15 and 7, and is twisted at its end, as shown at 25, around the other top member 15. The second suspension member 8 is twisted as at 16, around the top member 5, the parts 7 and 8 being in contact.

A coat, having been worn, shapes itself to 40 the shoulders, neck and upper portion of the back of the wearer, and the shape thus assumed, it is desirable to retain. When a

coat hanger of ordinary bowed construction is resorted to, the coat conforms to the bow of the hanger, and the shape assumed by engagement with the body of the wearer, is lost. There is, therefore, a very good reason for forming the projections indicated at 4, the slant of the arms 3 toward the base 1, creating the projections. There is, further, 55 an ample reason for inclining the parts 15 and 5 away from the base 1, since, owing to this construction, the angle at 6 is formed. The part 5 cannot slip to the right, Fig. 1, because a portion of the said part is lodged 60 at 10 in the angle 6 and is held positively. The suspension member 8 cannot move to the left, because it abuts against the suspension member 7, and the suspension member 8 cannot move readily to the right, because 65 the part 5 is disposed at an angle to the base 1, and at an acute angle to the part 8. A secure and positive lock is afforded at the place where the suspension members 7 and 8 are joined to the upper part of the hanger, 70 and the hanger cannot become distorted owing to the sliding of the coils 25 and 16 on the parts which they surround.

I claim:—

A coat hanger comprising a base having 75 upstanding end members merging into arms which slant toward the base to define prominent projections at the points where the end members join the arms, the arms merging into top members which slant away from 80 the base, one top member being bent upon itself to define an angle and to form first and second suspension members, one top member being lodged in said angle and being engaged around the other top member, 85 the second suspension member being engaged around the first specified top member.

In testimony that I claim the foregoing as my own, I have hereto affixed my signature in the presence of two witnesses.

HARRIET E. KELLEY.
